UNITED STATES PATENT OFFICE

2,012,931

SPRING COVER

Samuel Taylor, Chicago, Ill., assignor of one-half
to Eleanor Tevander Taylor, Chicago, Ill.

Application October 15, 1934, Serial No. 748,287

17 Claims. (Cl. 267—37)

This invention relates to certain new and useful improvements in metal spring covers for vehicle springs of a type adapted to closely embrace the spring and extend longitudinally thereof; and is 5 more particularly directed to the special combination of a plurality of sections which can be readily applied to the spring, or removed therefrom without the destruction of the cover, and thoroughly protect the spring against the accumulation of foreign matter.

Thus, an object of my invention is the provision of a flexible metal cover which shall be simple in construction, economical to manufacture, and consisting of a series of sections flexibly secured 10 together at their medial portions, and with the sections assembled together in this manner the entire cover may be readily applied upon the spring as a single unit and locked thereon by suitable locking means and as readily removed.

Another object of my invention is the provision 15 of a spring cover consisting of a plurality of sections, the side and bottom portions arranged to provide overlapping engagement with each other, the bottom portions, or flange portions, of each section folded to lie in the same plane with their longitudinal free edges in substantial abutment and having reinforcing plate members with locking 20 projections fabricated to said free edges, and locking plates overlying and locking said free edges in position to secure the cover upon the 25 spring.

With the above and other objects in view which will appear as the description proceeds, my invention resides in the novel construction, combination, and arrangements of parts substantially as hereinafter described and more particularly defined by the appended claims, it being understood that such changes in the precise embodiment of the herein disclosed invention may 30 be made as come within the scope of the claims.

In the accompanying drawings, I have illustrated one complete example of the physical embodiment of my invention constructed according to the best mode I have so far devised for the practical application of the principles thereof, and in which:—

Figure I is a fragmentary side view of a conventional semi-elliptic spring equipped with a spring cover constructed in accordance with this invention;

Figure II is a fragmentary top plan view of a spring equipped with the cover constructed in accordance with this invention;

Figure III is a fragmentary bottom plan view

of a spring equipped with the cover constructed in accordance with this invention;

Figure IV is a fragmentary, enlarged sectional view taken longitudinally through the shackle end portion of a spring equipped with the cover constructed in accordance with this invention, on the plane of the line IV—IV, of Figure II;

Figure V is a fragmentary, enlarged sectional view illustrating a modification of the construction shown in Figure IV;

Figure VI is a fragmentary, enlarged sectional view taken longitudinally through a spring with the cover embodying this invention applied thereon, showing the position of one of the flexible joint securing members on the top, and one of the removable locking members on the bottom, prior to the final assembled position;

Figure VII is an enlarged transverse sectional view of a spring and the cover embodying this invention, taken through Figure II on the plane of the line VII—VII;

Figure VIII is an enlarged, fragmentary side view illustrating the flexible joint portion of the cover embodying this invention;

Figure IX is a plan view of a metallic blank used to form a securing clip to be applied upon the medial portions of the adjacent spring cover sections embodying this invention;

Figure X is a fragmentary perspective view of a laminated spring equipped with one of the spring cover sections constructed in accordance with this invention illustrating the reinforcing members and locking members located on the bottom of the spring cover section;

Figure XI is a fragmentary perspective view of a flange portion of one of the spring cover sections embodying this invention and illustrating how the locking projections are formed out of the reinforcing members;

Figure XII is a fragmentary perspective view of the locking plate with a wedge shaped aperture and locking means constructed in accordance with this invention, and illustrating the position of the locking member prior to its application to a spring cover unit;

Figure XIII is a plan view of the blank for forming the end section of the spring cover embodying this invention, said section to be assembled adjacent that end of spring forming the shackle eye;

Figure XIV is a plan of a blank for forming the intermediate spring cover sections, also the rear end sections which are later trimmed to desired length;

Figure XV is a sectional view through any one

of the cover sections prior to assembly upon the spring, showing the desired formation of the section to permit the same to be sprung upon the spring.

5 Referring more particularly to the accompanying drawings, in which like numerals designate like parts throughout the several views, 10 designates a conventional semi-elliptic spring provided with a long top leaf 11, with the usual eye 10 12' surrounding a tubular shackle bushing 12, and a plurality of progressively shorter leaves 14 which are secured together by the bolt 15 and nut 16.

15 The arrangement and assembly of the spring cover parts incorporating this invention are so arranged such as to enclose the portion of the spring, between the thicker portion where it is secured to an axle or frame member of the vehicle and the small end or shackle eye end of the spring, with a wrapper of weatherproof fibrous 20 material and a single thickness of the metal, as near as possible, to provide a dirt-proof metallic cover with overlapping side portions, jointed top portions and locked bottom flange portions, thus allowing the flexing of the spring with least resistance.

25 In the illustrative embodiment of the invention, I provide a series of sections or units, 17, 18, 19, 20 and 21, each embracing four sides of the spring previously wrapped with the fibrous 30 wrapper 22.

35 The end section 17, shown in Figures I, II, and III, is formed of a single blank of thin metal, as shown in Figure XIII, having a top portion 25 extending along the upper side and adjacent the shackle end of the spring 10, side portions 26 extending along and embracing the edges of the spring leaves 11, and 14, and with flanges 27 formed to lie along the bottom side of the spring, said flanges lying in the same plane with each 40 other and having their longitudinal free edges in substantial abutment, said flanges having reinforcing members 28, welded or otherwise secured to the same along their free edges. The reinforcing members 28, each having a plurality of 45 projections or locking lugs 29, punched from their free edge portions and formed to extend outwardly and above the free edge of the flange 27. When the flanges 27 are in substantial abutment, the reinforcing members 28 and locking members 29 50 are also in substantial abutment. Cooperating with the projections 29, is a locking plate 30 having a plurality of apertures 31 and a plurality of locking tabs 32; a fragmentary portion of a plate 30 being shown in Figure XII. As a method of 55 sealing the shackle eye end of section 17, the extreme medial portion 17' adjacent said shackle eye is formed downwardly and inwardly away from said shackle eye to be in frictional contact with the upper portion of leaf 11, the bottom 60 portions of flanges 27 extending outwardly so that the end portions of same come into frictional contact with lower portions of spring eye 12', as clearly illustrated in Figure IV.

65 A slightly modified form of this desired seal is shown in Figure V, where the shackle eye ends of flanges 27 are rolled or spiralled inwardly away from shackle eye end of spring with their free edges in substantial abutment forming seal 13.

70 The spring cover sections 18, 19, 20 and 21 shown in Figures I, II, and III, are similarly constructed as described above regarding section 17; having top portions 35, side portions 36, bottom flanges 37, reinforcing members 28, locking 75 projections 29, locking plates 30, and locking tabs

32. Said sections are so arranged as to be in overlapping relation, the side and bottom members 36 and 37, of section 18, projecting over the adjacent overlapping portions 26 and 27, of section 17, the side and bottom members 36 and 37, of section 19, projecting over the adjacent overlapping portions 36 and 37, of section 18, and similarly with sections 20 and 21.

10 The above cover sections in assembled position are hingedly or flexibly secured together only at their medial portions 40, so as to accommodate the flexure of the spring 10. The medial connecting portions 40 are formed as flanges to extend outwardly from the top plane of the cover, the two adjacent flanges of the adjacent 15 units or sections forming a V. These flanges 40 are adapted to receive a metal clip or seam cover 41 formed with two converging side members 42; said clip 41 to be of the same gage material, or heavier gage material than the cover if desired. 20 After the separate cover sections have been placed into position for assembly, the seam cover 41 is forced over the flanges 40 of the sections, and a suitable tool is brought into contact with the top portion of seam cover 41 compressing, or partially flattening the medial connecting flange portions 40 and side members 42 of the seam cover, so as to complete the interlock and form the 25 flexible joint and securing means between the units or cover sections. The seam covers 41 are 30 further provided with end flanges 43, shown in Figures VIII, and IX, extending downwardly to hold said covers in place and prevent clips 41 from becoming displaced through vibration, or other reasons, and said flanges 43 further enclose 35 the end portions of the joint to form a seal.

35 After the several spring cover sections have been secured together by the seam covers or joint securing means 41, the entire cover appears to be substantially a single unit 44, and ready for 40 assembly upon the vehicle spring 10, referred to above. It is preferable to assemble the entire cover as a unit by forming the sections into substantially the shape illustrated by the sectional view XV, so that the sections may be easily 45 sprung over the spring and ready for securing same upon said spring.

45 Before placing the spring cover on the spring 10, it is preferable to cover the spring with a lubricant such as graphited grease and then wrap 50 the same with a cover of suitable fibrous material such as canvas or burlap 22, whereby after the spring cover has been placed in position and secured upon the spring, the lubricant is retained within the wrapping and the spring leaves are 55 kept in condition for perfect performance.

55 The spring cover 44 may be secured to the spring 10, and held against longitudinal movement by any suitable locking means; however, I have shown, for example, a locking plate 33, 60 of steel or other metal, with two wedge shaped apertures 34 for each individual section of the cover. After the cover is placed upon the spring, the bottom flanges of the individual cover sections are pressed into abutment, the locking projections 29 on each reinforcing member likewise are in abutment and ready to be secured together. This arrangement allows the locking plate 33 to be placed upon said reinforcing members with projections 29 extending through the wedge 65 shaped apertures 34, after which by longitudinal movement of the locking plate in the direction of the arrow shown in Figure X, it creates a gripping action on the vertical portion 70 of projections 29. This also forces a portion 75

of the locking plate 30 beneath the horizontal portions 43 of projections 29. After this partial assembly is completed a suitable tool is brought into contact with the horizontal portion 50 of locking means 32, forcing the same downwardly, securing the projections 29 into locking engagement. After each section of the cover is secured to the spring in the above described manner, the spring cover 44 is substantially a single unit firmly secured to the spring 10. If for any reason it should become necessary to remove said cover 44, such as repairing the spring 10, it is apparent that one need but insert a suitable tool beneath the substantially horizontal portion 50 of locking member 32, raise the same out of locking engagement, and reverse the above described procedure.

From the foregoing you will see that I have shown and described the spring cover constructed with the flexible joints arranged along the top of the cover and with the locking plate along the bottom of the cover. If it were preferable to place the cover in an inverted position with the hinge joints along the bottom, and the locking means along the top of the spring, where access to the bottom of the spring is difficult, only a slight modification of the blanks shown in Figures XIII and XIV, is required, thus leaving the novel invention adaptable for either installation.

It will be further noted from the foregoing that I have provided a very simple and economical vehicle metal spring cover, adapted to permit the spring to be first wrapped with the usual lubricant retaining fabric, said cover to be applied and removed from the spring as often as desired and obviate the necessity of removing the spring from the vehicle or destroying any part of the spring cover assembly, requiring no loading machine to flatten the spring, and very little labor or time, which is the usual drawback of the various metal spring covers commercially used at the present time.

In order to incorporate the above advantages, simplicity, flexibility, strength, economy and others, I have provided a spring cover formed of a plurality of relatively movable sections, said body portions of the cover preferably constructed from very thin, durable, flexible metal, said metal substantially too thin to permit the locking members to be constructed therefrom; however, I have provided the desired reinforcing members along the longitudinal abutting edges of the cover sections, and from these reinforcing members I have punched or formed the locking projections which are locked together by suitable means, such as shown and described herein, by a novel removable locking plate. Said flexible metal spring cover completely encloses the spring on four sides against moisture and dirt.

What I claim as my invention is:—

1. In a vehicle spring cover, the combination of a plurality of relatively movable sections, each section having a plurality of flanges in overlapping relation with flanges of adjacent sections, connecting means engaging transversely extending flanges formed on the medial portions of adjacent sections, each section provided with reinforced longitudinal flanges and means carried thereby to lock each section of the cover on the spring.

2. In a vehicle spring cover, the combination of an inner lubricant impervious lining surrounding the spring laminations, and an outer metallic casing comprising a plurality of substantially over-lapping movable sections, connection means

engaging the medial portions of adjacent sections, each section provided with reinforced longitudinal flanges in substantial abutment, locking lugs extending outwardly therefrom, and means carried thereby to lock each section of the cover on the spring. 5

3. In a spring cover of the character described, the combination of a plurality of individual sections surrounding four sides of a spring, separate connecting means for engaging transversely extending flanges formed on the medial portions of adjacent sections, each section provided with reinforced longitudinally inwardly extending flanges, and means formed integral therewith to cooperate with a locking plate to secure each section of the cover to the spring. 10

4. In a spring cover of the character described, the combination of a plurality of individually connected movable sections, having longitudinal inwardly extending flanges, reinforcing members permanently secured to the longitudinal free edge portions of the inwardly extending flanges of each section, said reinforcing members provided with non-yielding lugs for association with locking plates provided with apertures and locking means to secure each section of the cover on the spring. 20

5. In a spring cover for laminated springs, the combination of a plurality of separate relatively movable sections, adjacent end portions of each section provided at its medial end portions with transversely extending flanges adapted for engaging with transverse clamping clips having converging side members, each section further provided with reinforced longitudinal flanges with locking lugs thereon adapted to engage a single locking plate having apertures to receive said lugs, and locking means on said plate to secure each section rigidly upon the spring. 30

6. In a spring cover of the character described 40 a plurality of separate, relatively movable sections hingedly connected together only at their medial end top portions, each section having longitudinal reinforced inwardly extending flanges with locking lugs thereon, the entire cover adapted to snugly fit the top, sides, and bottom portions of a laminated spring when each section is separately secured on the spring by locking means associated with said locking lugs formed from the flange reinforcing means, the reinforced inwardly 45 extending flanges of each section lying in abutment in the same plane. 50

7. A cover for laminated vehicle springs comprising a plurality of separate metallic sections, having reinforced longitudinal free edges, and 55 adapted to snugly fit the top, sides and bottom portions of a spring, said cover provided with transversely flexible connections securing the medial portions of adjacent sections together, each section having side and bottom portions adjacent said flexible connections overlapping similar adjacent portions, and means for securing together the reinforced longitudinal free edges of each section whereby each section is separately secured to the spring. 60

8. A cover for laminated vehicle springs comprising a plurality of metallic sections having reinforced longitudinal free edges and adapted to snugly fit the top, sides, and bottom portions of a spring, said cover provided with transversely 70 flexible connections securing the medial end portions of the top portions of adjacent sections together, having side and bottom portions adjacent said flexible connections overlapping similar adjacent portions, locking lugs struck from the 75

reinforcing member and means for securing the longitudinal free edges of each section together in substantial abutment whereby each section is separately secured to the spring with adjacent sections hingedly connected together to form a substantially flexible cover.

9. A cover for laminated vehicle springs comprising a plurality of metallic sections, having longitudinal free edges adapted to snugly fit the top, sides, and bottom portions of a spring, said cover provided with transversely flexible connections, having depending side members and depending end members to secure and lock the medial portions of adjacent sections together, each section having sides and bottom portions adjacent said flexible connections overlapping similar adjacent portions, rigid lugs struck from reinforcing members secured to the longitudinal free edges of each section, and means for securing the longitudinal free edges of each section together in substantial abutment along the bottom of the spring.

10. A removable spring cover for laminated vehicle springs comprising a plurality of metallic sections having longitudinal free edges adapted to snugly fit the top, sides and bottom portions of a spring, provided with transversely flexible hinge connections, with depending locking means, securing the medial portions of adjacent sections hingedly together, said sections having side and bottom portions adjacent said flexible connections overlapping similar adjacent portions, the longitudinal free edges of each section provided with reinforcing members formed with locking lugs, extending outwardly therefrom, and locking plates provided with apertures and releasable means overlying said reinforcing members, said apertures to receive said lugs for securing said free edges and said lugs together in substantial abutment along the bottom of the spring whereby each section is secured to the spring.

11. A cover for laminated vehicle springs comprising a plurality of metallic sections having longitudinal free edges adapted to snugly fit the top, sides, and bottom portions of a spring, provided with transversely flexible connections securing the medial portions of adjacent sections together, having side and bottom portions adjacent said flexible connections overlapping similar adjacent portions, the longitudinal free edges of each section provided with reinforcing members formed with a plurality of locking lugs extending outwardly therefrom, and locking plates provided with a plurality of apertures to receive said lugs and releasable means adapted to lock said lugs in said apertures and thus secure said sections to the spring.

12. A cover for laminated vehicle springs comprising a plurality of metallic sections having longitudinal free edges adapted to snugly fit the top, sides, and bottom portions of a spring, provided with transversely flexible hinge connections with depending locking end members to hinge and lock the medial portions of adjacent sections together, each section having side and bottom portions adjacent said flexible connections overlapping similar adjacent portions, the longitudinal free edges of each section in substantial abutment and provided with reinforcing members formed with a plurality of rigid locking lugs extending outwardly therefrom and an individual locking plate for each section, provided with a plurality of apertures to receive said rigid lugs and releasable means adapted to lock respective lugs in said

apertures and thus secure said sections to the spring.

13. A cover for laminated vehicle springs, comprising a plurality of metallic sections having longitudinal free edges adapted to snugly fit the top, sides, and bottom portions of a spring, provided with transversely flexible connections securing the medial portions of adjacent sections together, having side and bottom portions adjacent said flexible connections overlapping similar adjacent portions, the longitudinal free edges of each section provided with reinforcing members formed with locking lugs punched from the longitudinal free edges thereof and extending outwardly therefrom, and locking plates provided with apertures to receive said lugs and releasable means overlying said reinforcing members and adapted to engage the respective locking lugs to lock said sections upon the spring with said longitudinal free edges and locking lugs in substantial abutment.

14. A cover for laminated vehicle springs comprising a plurality of metallic sections, having longitudinal free edges adapted to snugly fit the top, sides, and bottom portions of a spring, provided with transversely flexible connections securing the medial portions of adjacent sections together, having side and bottom portions adjacent said flexible connections overlapping similar adjacent portions, the longitudinal free edges of each section provided with reinforcing members formed with a plurality of locking lugs punched from the longitudinal free edges thereof and extending outwardly therefrom, and individual locking plates for each section provided with a plurality of apertures and releasable horizontally extending locking means, the apertures of each locking plate receiving the locking lugs of the reinforcing members of a section, and the horizontally extending means being bent down to hold the locking lugs in the apertures and thus secure the sections individually upon the spring.

15. A removable cover for laminated springs, the combination of a plurality of individual relatively movable sections, each section provided at its medial end portions with flanges engaging transverse clamping clips having converging side members and downwardly extending end members so that the sections are hingedly connected and locked together, each section further provided with reinforced longitudinal free edges with rigid locking lugs thereon, and locking plates with wedge shaped apertures, and releasable locking means adapted to receive and lock said lugs together, whereby each section is individually secured to said spring and adapted to be easily removed.

16. The combination, with a laminated spring which has one of its leaves projecting beyond the other leaves of the spring and terminating in a spring eye arranged transversely of said leaf and forming a shackle housing, and a flexible metal spring cover consisting of a plurality of individual sections, adapted to snugly fit the top, sides and bottom portions of said spring and provided with transversely flexible hinge like connections securing the medial portions of adjacent sections together, having side and bottom portions adjacent said hinge like connection overlapping similar adjacent portions, the shackle eye end of said cover provided at its upper side with a transverse, integral folded portion in contact with the upperside of the longest leaf of said spring, and provided at its under side with a transverse, integral rolled portion in contact with the under- 75

side of said longest leaf, said shackle eye end of said cover forming a dual oil and dirt seal.

17. A removable cover for laminated springs, the combination of a plurality of individual relatively movable sections, each section provided at its medial end portions with flanges engaging transverse clamping clips having converging side members and downwardly extending end members, so that the sections are hingedly connected and locked together each section further provided with reinforced longitudinal free edges with rigid locking lugs thereon, and locking plates

with wedge shaped apertures and releasable locking means adapted to receive and lock said lugs together, whereby each section is individually secured upon the spring, the shackle eye end section of the spring cover provided with means to form a dual oil and dirt seal by having a folded top portion in contact with the upper-side of spring leaf forming the shackle or the spring eye, and said cover provided at its underside, with a transverse rolled portion in contact with the underside of said spring leaf. 5

SAMUEL TAYLOR.
